UNITED STATES PATENT OFFICE

2,479,050

PAPER CAN MAKING MACHINE

Melvin H. Sidebotham, Newton, Mass.

Application March 21, 1945, Serial No. 583,973

15 Claims. (Cl. 93—39.2)

1

This invention relates to apparatus for producing round, paper containers by a sequence of operations.

More particularly the invention relates to improvements in machines for making round paper containers by assembling together two cylindrical sleeves and securing a bottom element in one end of the assembled sleeves.

My invention consists in novelties of construction and in the coordination of novel devices. I do not confine my invention to the form shown, as changes in construction and operation may be made without departing from the spirit of my invention.

The embodiment of my invention described and claimed in this present application contemplates the production by automatic machinery of paper containers by the method described in my copending application Serial No. 556,345, filed September 29, 1944 which has become abandoned. However, my present invention is not limited to machines for producing containers by the particular method described in said copending application.

One object of my invention is to provide a machine for assembling one cylindrical paper sleeve over another cylindrical paper sleeve and then securing a paper bottom to one end of the sleeve assembly.

Another object of my invention is to provide a machine which will, by a sequence of operations produce cylindrical paper containers singly, successively and continuously, in a rapid, economical and efficient manner.

Other more specific objects and advantages of the invention will be apparent to persons skilled in the art as the same becomes better understood by reference to the following description, taken in connection with the accompanying drawings, in which I have illustrated one practical embodiment of my invention, and wherein:

Figure 1 is a front elevation of the machine.

Figure 2 is a partial section at 2—2 of Figure 3.

Figure 3 is an elevation of the turret assembly.

Figure 4 is a partial section at 4—4 of Figure 1.

Figure 5 is a partial section at 5—5 of Figure 1.

Figure 6 is a partial section at 6—6 of Figure 1.

Figure 7 is a front elevation of the apparatus for placing cylindrical paper sleeves over the mandrels of the machine.

Figure 8 is a side view of Figure 7.

Figure 9 is a front view of the mechanism which cuts a bottom disc element from a web and inserts the bottom disc element into the end of a cylindrical paper sleeve.

2

Figure 10 is a side elevation of Figure 9 with a portion cut away to more clearly illustrate the bottom assembling mechanism.

Figure 11 is a front elevation of the device for crimping inwardly ends of the cylindrical sleeves.

Figure 12 is a side view of Figure 11.

Figure 13 is a front view of the device for removing the completed paper container from the mandrel of the machine.

Figure 14 is a side view of Figure 13.

Figure 15 is a plan view of one of the mandrels on which the paper containers are formed.

Figure 16 is a front elevation of Figure 15.

Figure 17 is a plan view of a mandrel with an inner paper sleeve positioned thereon.

Figure 18 is a plan view of the mandrel with an inner paper sleeve positioned thereon, and with a bottom disc assembled within the end of the said sleeve; a portion of the bottom former ring 20 98 and bottom former block 105 are also shown.

Figure 19 shows the end edge of the cylindrical paper sleeve turned inwardly over the bottom element; a portion of the crimping tool 35 for turning the end edge of the sleeve is also illustrated.

Figure 20 is a plan view of a mandrel with two paper sleeves assembled thereon.

Figure 21 is a plan view of the completed paper can mounted on a mandrel of the machine; the tool 35 for crimping the ends of the assembled paper sleeves over the flanged edges of the bottom closure is also shown.

Figure 22 is a side view of the cylindrical paper sleeve which comprises the inner member of the 35 paper container.

Figure 23 is an end view of Figure 22.

Figure 24 is an edge view of the paper disc from which the bottom on the container is formed.

Figure 25 is a side view of the bottom disc shown 40 in Figure 24.

Figure 26 is a side view of the bottom disc formed to provide a flange thereon.

Figure 27 is an end view of Figure 26.

Figure 28 is a side view of the inner sleeve with the flanged bottom disc assembled therein.

Figure 29 is an end view of Figure 28.

Figure 30 is the same as Figure 28 except that one end of the sleeve is turned slightly inward over the flanged bottom disc.

Figure 31 is an end view of Figure 30.

Figure 32 is a side view of the outer, cylindrical sleeve of the paper container.

Figure 33 is an end view of Figure 32.

55 Figure 34 is a side view of the assembly shown

in Figure 30 positioned within the sleeve shown in Figures 32 and 33.

Figure 35 is an end view of Figure 34.

Figure 36 is a side view of the completed paper container.

Figure 37 is an end view of Figure 36.

Figure 38 is a partial section at 38—38 of Figure 36.

Similar reference characters indicate similar parts or features in all of the views.

It will aid toward an understanding of the operation of the machine and of the method of fabricating the cylindrical paper containers to first explain generally the action of the machine which effects the production of cylindrical paper containers by a sequence of operations.

Cylindrical paper sleeves 1 (Figs. 22 and 23) are placed in a supply hopper 56 (Figs. 1 and 8). From the said supply hopper 56, the paper tubes are fed, by gravity, singly and successively into position to be thrust horizontally over a mandrel. The said mandrel is one of six similar mandrels mounted on a turret which is horizontally pivoted and so actuated as to move each mandrel successively from one position to another until a paper container is completed and deposited in a receiving hopper.

From the position where the paper sleeve 1 is pressed over one of the mandrels 40, the turret 6 revolves horizontally to move the paper sleeve 1 into position to receive the bottom disc 2 which is cut from a web and then formed to provide a flange 3 (Figs. 24 to 29 inclusive).

The mandrel is next moved to a position where the end edges of the sleeve 1 are turned slightly inward as shown in Figs. 19, 30 and 31.

The next operation consists in sliding an outer paper sleeve 4 (Figs. 32 and 33) over the inner paper sleeve 1, as shown in Figure 20.

The sleeve assembly is then moved to a position to inwardly crimp the adjacent ends of the sleeves 1 and 4 over the flange 3 of the bottom 2, to complete the paper container as shown in Figures 21, 36 and 37.

The turret then operates to move the mandrel, carrying the completed can, to a position where the container is removed from the mandrel. The mandrel is then moved to the first station to receive another paper sleeve 1 to begin another cycle of operations.

Machine frame and machine operating mechanism

Referring to Figures 1 to 6 inclusive, the several cooperating mechanisms comprising the complete machine are supported by a base frame 5 having a horizontally rotatable turret 6 mounted on its upper structure.

Mounted within the base of frame 5 is an electric motor 7 for driving the machine. The said motor 7 is operated continuously while the machine is in use. A pinion 8 (Fig. 6) mounted on the shaft of the motor meshes with drive gear 9 secured to drive shaft 10 journaled in frame 5. A flywheel 11 is secured to one end of the drive shaft 10. A friction clutch internal member 12 is slidably secured to the drive shaft 10. The external clutch member 13 is driven by the internal clutch member 12 operating in the conventional manner. Integral with the external clutch member 13 is a pinion 14 which meshes with gear 15 journaled on shaft 16 (Fig. 5). A chain sprocket 17 is integrally joined to gear 15. The chain sprocket 17 serves by means of chain 18

to drive chain sprocket 18 (Fig. 4) secured to shaft 20. Also secured to said shaft 20 is a bevel gear 21 which operates in the conventional manner to drive bevel gears 22, 23, 24, 25 and 26 which are secured to shafts 27, 28, 29, 30 and 31 respectively.

Shaft 28 (Fig. 4) drives the mechanism shown in Figures 7 and 8 for positioning a tubular paper sleeve 1 (Fig. 22) over the mandrel 40 in the first 10 operation for producing the paper container described in Figures 22 to 38 inclusive.

Secured to shaft 29 (Fig. 4) is a chain sprocket 32 which operates to drive mechanism, not necessary to describe, for causing the horizontally 15 rotatable turret 6 (Figs. 2 and 3) to rotate for moving the work carrying mandrels secured thereto, progressively to the several stations which operate to produce the paper container described. Also secured to and driven by shaft 20 20 (Fig. 4) are cams 33 and 34 which operate the mechanism shown in Figures 9 and 10 for die cutting, forming and inserting a bottom disc 2 (Fig. 26) into the end of the tubular sleeve 1 positioned on the mandrel.

Shaft 30 (Fig. 4) has secured thereto a cam 420 which drives that part of the mechanism shown in Figures 11 and 12 for moving the rotating, crimping disc 35 horizontally into engagement with the tubular sleeve 1 mounted on the 30 mandrel. A motor 33 is provided with a belt pulley 34 which by means of belt 36 drives the crimping tool 35, to turn slightly inwardly the end of the tubular sleeve 1 over the flange 3 of the bottom disc 2.

Shaft 31 (Fig. 4) operates to drive mechanism such as is shown in Figures 7 and 8 which operates to feed a tubular sleeve 4 (Figs. 32 and 33) over the tubular sleeve 1 positioned on the mandrel. This mechanism is the same as the mechanism 40 operated by shaft 28 for placing the tubular sleeve 1 on the mandrel. The only difference between the mechanisms driven by shafts 29 and 31 is that the mechanism driven by shaft 31 is made to handle a paper sleeve of slightly larger 45 dimensions. At this stage of production the container is in the condition illustrated by Figures 34 and 35.

Shaft 29 (Fig. 4) serves to drive mechanism of the same character as shown in Figures 11 and 50 12, previously described as driven by shaft 30. The only difference between the mechanisms driven by shafts 30 and 29 is that the crimping tool 35 in the latter instance is pressed further 55 against the tube assembly on the mandrel, to firmly crimp the adjacent ends of the tubes 1 and 4 against the flange 3 of the disc 2, to complete the paper can as illustrated by Figures 36 and 37.

The shaft 27 (Fig. 4) operates the mechanism shown in Figures 13 and 14 for successively removing the completed containers from the mandrels and depositing them into a hopper 47 from which they are picked up for use.

After the electric motors 7 and 33 have been started, the several container fabricating mechanisms of the machine are started and stopped by means of a hand lever 37 (Figs. 1 and 6) secured to operating shaft 38 which is operatively secured in the base of frame 5. The operating shaft 38 has secured thereto a clutch yoke 39 60 for causing the internal clutch member 12 to operatively engage external clutch member 13 to start the container fabricating mechanisms. When the machine is to be stopped the lever 37 65 is operated to cause the clutch yoke 39 to disengage the internal clutch member 12 from the

external clutch member 13, thus stopping the fabricating operations of the machine.

Turret assembly

Referring to Figures 1, 2 and 3, a turret 6 is 5 rotatably mounted on the upper part of base frame 5. The mechanism for rotating the turret 6 has been omitted for the sake of clarity, any suitable means may be employed to cause the turret to rotate one-sixth of a revolution and then 10 dwell for a very short interval and then rotate another one-sixth of a revolution, and so on as long as the machine is in operation.

While one part of the machine is performing an 15 operation on one container, other parts of the machine are at the same time performing other operations on other containers, all of said containers following one another progressively around the machine and are delivered therefrom as complete paper containers as shown in Figures 36 and 37.

The turret 6 has secured thereto six mandrel assemblies spaced equidistant about the said turret. Each mandrel assembly includes a mandrel 40 (Figs. 2, 3, 15 and 16) having a base shoulder 42, a secondary shoulder 43 and a mandrel block 41. Each mandrel block 41 is secured to a vertical surface of the turret 6. The said mandrel block 41 is provided with three recesses 44, within which tie pins 45 are secured. The outer ends of tie pins 45 support a face plate 46 which is provided with a central opening 47 through which the tubular sleeves of the container are fed into position on the mandrel 40.

In performing certain of the can fabricating operations it is necessary to securely hold the tubular assembly to the mandrel.

Pivots mounted on the upper and lower tie pins 45 of each mandrel assembly are two holding brackets 48 connected together by tension spring 49 anchored to ends of said brackets 48. The opposite ends of holding brackets 48 are provided with pins 50 on which are rotatably mounted rollers 51 and pivotally mounted clamps 52. The tension springs 49 serve to hold the sleeve clamps 52 open and against holding pins 53 which extend inwardly from the face plates 46.

Positioned around and operatively free of the turret 6 are two clamp operating rings 54, one ring positioned over and adjacent to the mandrel assemblies and the other positioned under and adjacent to the said mandrel assemblies. The said clamp operating rings 54 are stationary with respect to the turret and the mandrel assemblies.

In the operation of the turret 6 the rollers 51 ride on the inner surfaces of the clamp operating rings 54 which are provided with raised surfaces 55. When the turret 6 is rotated the rollers 51 at predetermined positions ride up onto the raised surfaces 55 of the clamp operating ring, with the result that the rollers 55 are moved slightly toward each other causing the sleeve clamps 52 to securely clamp to the mandrel the tubular paper sleeve mounted thereon.

Sleeve feeding mechanism

In the first operation for producing the paper container described, a supply of tubular paper sleeves 1 are placed in a supply hopper 56 (Figs. 7 and 8). The said sleeves 1 are fed singly and successively into position to be pressed over the mandrel 40 and against the outer edge of the secondary shoulder 43. The shaft 28 has its outer end journaled in bracket 57, and has secured thereto a cam 58, and a bevel gear 59 which

meshes with bevel gear 60 secured to shaft 61 journaled in said bracket 57. The rotation of cam 58 actuates the cam follower 62 rotatably secured to the end of lever 63 pivoted on pin 64 secured to arm 65 of bracket 57 which is mounted on the base frame 5. Integral with the hub of lever 63 is a lever 66 provided at its outer end with a pin 67 to which is connected the lower end of link 68. The upper end of link 68 is pivotally connected by means of pins 69 to the jaw 70 pivoted on pin 71 secured in bracket 57. Thus it will be apparent that the rotation of cam 58 will cause the jaw 70 to pivot upwards at intervals so that the top portion of jaw 70 will meet the top of fixed jaw 72 which is secured to said pin 71 to form a closure for holding a sleeve 1 in position to be pressed over one of the mandrels 40 on the turret 6.

The next operation to be performed is to press 20 the sleeve 1, which is positioned between jaws 70 and 72, into position on the mandrel 40. This is accomplished by the mechanism now to be described. The bevel gear 59 (Figs. 7 and 8) meshes with and drives bevel gear 60 which is secured to shaft 61. A cam wheel 73 is secured to and is driven by said shaft 61. A cam follower 74, which is operatively retained within cam race 75 of the cam wheel 73, is rotatably secured to the end of cam follower lever 76, which is pivoted on pin 77 secured to bracket 57. A lever 78 is secured to the said pin 77. The upper end of said lever 78 is pivotally connected to one end of link 79. The other end of the link 79 is pivotally connected to the outer end of thrust rod 80 which is slidably held by bearing 81 secured to bracket 57. The inner end of the thrust rod 80 supports a thrust plate 82 which operates to press the paper sleeve 1 positioned between jaws 70 and 72 into position on the mandrel 40. It will be obvious that the rotation of cam wheel 73 will actuate the several elements just described to place paper sleeves on the mandrels in the sequence described.

At this stage of production a paper sleeve 1 is 45 in position on mandrel 40. The turret 6 is then rotated one-sixth of a revolution, with the result that the mandrel 40 with the sleeve 1 positioned thereon is advanced to a station to have a bottom disc 2 inserted into the end of the sleeve 1. While the mandrel 40 carrying the sleeve 1 is 50 being advanced, another mandrel is at the same time being advanced into position to receive a paper sleeve thereon.

Bottom forming mechanism

Referring to Figures 1, 9 and 10, there is illustrated mechanism for forming and inserting a bottom disc 2 into the end of the paper sleeve 1 positioned on mandrel 40.

In the operation for providing a bottom for the container, a supply roll of paper 90 is rotatably supported on standards 91 secured to a support block 92 mounted on plate 86 secured to base frame 5. From the supply roll 90 a web 96 of paper is drawn at predetermined intervals by 60 means not necessary to describe. The web 96 is advanced over roller 93 rotatably journaled in bearings 94 secured to bearing plate 95 supported by plate 86. From the roller 93 the web passes downward and between a die block 97 and a former ring 98. The die block 97 is secured to the top plate 86 and braced by angle 99 secured to bearing plate 95. The former ring 98 is also supported by plate 86. Slidably mounted in the die block 97 is a punching die 100 which serves 65 to cut a bottom disc 2 (Figs. 24 and 25) from the

web 96 and deposits the bottom disc 2 within the former ring 98. The die 100 is actuated by means of toggle links 101 and 102. The lower ends of the toggle links 102 are connected to the die 100 and the upper ends are connected by means of pin 103 with the upper ends of toggle links 101 and the upper end of connecting link 104 the lower end of which is connected to link bar 89. The lower ends of toggle links 101 are anchored on support block 92.

A cam wheel 83 and a cam roll 84 are secured to shaft 29. The outer end of shaft 29 is journaled in bearing 85 hung from plate 86. A cam follower 87 is secured to guide yoke 88 which has its lower end yoked over shaft 29 and its upper end operatively secured to the lower end of link bar 89. It will be apparent that the rotation of cam wheel 83 will, by means of the cam follower 87 secured to guide yoke 88, cause the said guide yoke to move up and down at predetermined intervals, with the result that the toggle links 101 and 102 will actuate the die 100 to punch out bottom discs from the web 96 and deposit them singly and successively within the former ring 98.

After the bottom disc 2 has been cut from the web 96 and placed within the former ring 98, a circular former block 105 slidably mounted within the die 100 operates to press the bottom disc 2 through the circular opening 106 in the former ring 98, thus forming a flange 3 (Fig. 26) on the bottom disc 2. The further movement of the former block 105 positions the formed bottom disc inside the end of the paper sleeve 1 on the mandrel 40. The former block 105 is then withdrawn from engagement with the bottom disc, thus leaving the bottom disc in position within the end of paper sleeve 1.

The former block 105 is actuated by means of a tubular rod 108 secured at one end to former block 105. Secured to the mid-portion of tubular rod 108 is a clamp 109 which is operatively connected, by means of pin 110, with the upper end of lever 111 pivoted on pin 112 secured in bracket 113 hung from plate 86. Secured to the hub of lever 111 is a cam follower lever 114 having thereon a follower lug 115 which ride in cam groove 116 in cam roller 84. Thus the rotation of cam roller 84 will, by means of levers 111 and 114, cause the tubular rod 108 to actuate die block 105 at intervals to form flanges 3 on bottom discs 2 and deposit the said bottom discs in place within the paper sleeve 1. In order to be certain that the bottom disc 2 will not be drawn away from the end of the paper sleeve 1 when the former block 105 is withdrawn, a holding disc 107 operates to hold the bottom disc 2 in position until the former block 105 is withdrawn and free from contact with the bottom disc.

The holding disc 107 is positioned in a recess in the face of former block 105, and is operated by holding disc rod 117 one end of which is secured to said holding disc. Slidably mounted on holding disc rod 117 is a trip collar 118. While the bottom disc forming operation is being performed, the holding disc rod 117 and the trip collar 118 move with the former block 105. However, after the former block 105 has positioned the bottom disc 2 within the sleeve 1, the former block is withdrawn, while the holding disc 107 acts to hold the bottom disc in place. The holding disc 107 is momentarily held in place by a locking device which prevents the holding disc rod from moving away with the former block. The said locking device comprising a locking lever 149 pivoted on pin 50 secured to projections 151

on support block 92. When the former block 105 is moved to engage a bottom disc 2 the locking collar 152 secured to the holding disc rod 117 is locked from outward movement by said locking lever 149. The trip collar 118 at this stage of operation is positioned close to the support block 92. After the former block 105 has been moved out of contact with the bottom disc 2, the further outward movement of the former block will cause the trip collar 118 to contact the release boss 153 on the trip lever 149 to raise the trip lever from engagement with the locking collar 152. The compression spring 154 then acts to move the holding disc rod outwardly, thus drawing the holding disc away from the bottom disc and into place within the recess in the forming disc 105.

A portion of the mechanism for advancing the web 96, after each die cutting operation, is omitted for the sake of clarity, any desired means will suffice. The web advancing means may be actuated by lever 155 (Figs. 9 and 10) pivoted on pin 156 secured in bearing 85. Integrally connected to the hub of lever 155 is a cam follower lever 157 which is actuated by cam 84. A lever 158 is secured to the hub of lever 155, and serves by means of spring 159 to hold the cam follower lever 157 in contact with the cam 84. The said tension spring 159 has one end secured to lever 158 and the other end of the spring anchored to bearing 85.

From the station where the formed bottom disc 2 is inserted into the end of tubular sleeve 1, the turret 6 is caused to rotate one-sixth of a revolution, to present the mandrel carrying the tubular sleeve 1 and bottom disc 2, to the station where the outer end of sleeve 1 on mandrel 40 is turned slightly inward over the flange 3 of the bottom disc.

Container crimping mechanism

Figures 1, 11 and 12 illustrate the mechanism for turning inwardly one end of the tubular sleeve 1 as shown in Figures 30 and 31. Secured to shaft 30 (Fig. 4) is a cam wheel 119 (Figs. 11 and 12) having a cam race 120 in which is positioned a cam roller 121 rotatably secured to the lower end of slide bar 122 which is slidably retained in toggle bracket 123 secured to base frame 5. The upper end of slide bar 122 is connected to the lower end of connecting link 124. The upper end of said connecting link 124 is operatively secured to the adjacent ends of toggle links 125 and 126. The lower end of toggle link 125 is pivotally anchored on pin 127 secured in toggle bracket 123, and the lower end of toggle link 126 is connected by means of pin 128 to thrust rod 129 which is slidably and horizontally supported in the toggle bracket 123. A crimping tool 35 is rotatably mounted on the end of thrust rod 129. The said crimping tool is rotatably driven by means of belt 36 from pulley 34 on motor 33. It will be obvious that the rotation of cam wheel 119 will, by means of the mechanism which it actuates, cause the rotating crimping tool 35 to be moved against the end of a tubular paper sleeve on mandrel 40 to turn the outer edge of said sleeve slightly inward.

After this operation has been completed the turret 6 is rotated one sixth of a revolution to advance, to the next station, the mandrel carrying the tubular sleeve 1 with the bottom closure 2 in place and with the outer edge of the paper sleeve 1 crimped slightly inward.

The next operation of the machine is to slide a tubular paper sleeve 4 over paper sleeve 1 to

produce an assembly as shown in Figures 34 and 35.

Mechanism for assembling the outer sleeve over the inner sleeve of the container

The mechanism which positions the outer sleeve 4 over the inner sleeve 1 is substantially the same in all respects as the mechanism which positions inner sleeve 1 on the mandrel 40 in the first operation of the machine. The only differences being a slight difference in the size of parts, made necessary by the differences in the size of the inner and outer sleeves. The mechanism illustrated by Figures 7 and 8 will serve to illustrate the means for assembling the outer sleeve 4 over inner sleeve 1 at the fourth station of the machine. The shaft 31 (Fig. 4) operates in the same manner as shaft 28 to operate mechanism shown in Figures 7 and 8.

After the outer sleeve 4 has been positioned over the inner sleeve 1 in the fourth operation of the machine, the turret 6 is again rotated one-sixth of a revolution to advance the container assembly to the position where the adjacent ends of the outer and inner sleeves 1 and 4 are crimped tightly over the flange 3 of the bottom closure disc 2.

Mechanism for performing the final crimping operation

The mechanism for performing the final crimping operation acts to crimp the adjacent ends of sleeves 1 and 4 to the condition illustrated by Figures 36, 37 and 38. This mechanism is substantially the same in all respects as the mechanism illustrated by Figures 11 and 12. The only difference being that the crimping tool 35 is thrust further against the end of the container in the final crimping operation than is done in the first crimping operation.

After the final crimping operation the turret 6 is again advanced one-sixth of a revolution to the position where the completed container is removed from the mandrel 40.

Mechanism for discharging the completed containers from the machine

When the completed container positioned on mandrel 40 reaches the sixth station of the machine, opposite the mechanism operated by shaft 29 which is shown in Figures 4, 13 and 14, the container is removed from the mandrel 40. The outer end of shaft 29 is journaled in discharge bracket 130 which is secured to base frame 5. Also secured to shaft 29 is a bevel gear 131 which meshes with bevel gear 132 secured to shaft 133 journaled in said bracket 130. A cam wheel 134, secured to and driven by said shaft 133, is provided with a cam race 135. A cam follower 136 operatively positioned in cam race 135 is rotatably secured to the lower end of lever 137 pivoted on pin 138 secured in bracket 130. The upper end of lever 137 has a fork member 139 engaging pins 140 on pull hub 141 slidably mounted on fixed shaft 142 which is secured in the upper end of bracket 130. The said pull hub 141 has a downwardly extending bar 143 to which is fastened a suction cup 144. The said suction cup 144 is provided with an air valve the stem 146 of which extends through the bar 143. In its normal position the valve is closed so that no air may pass into the cup except through the open mouth 145, but when the valve stem is pressed by outside means, air is admitted through the valve and into the suction cup 144, even though

the mouth of the suction cup is closed by being pressed against the bottom of a container.

A receiving hopper 147 secured to bracket 130 is provided to receive the containers from the machine. Secured to the upper portion of hopper 147, horizontally opposite the suction cup 144, is a trip bar 148 for engaging the valve stem 146 when the suction cup has drawn a container from the mandrel and positioned it over the discharge hopper 147. In the operation of this discharging mechanism the rotation of cam wheel 134 actuates lever 137 first to press suction cup 144 against the bottom of the completed container, in the conventional manner, to secure the container to the suction cup. The lever 137 then acts to draw the suction cup and the container to a position over the hopper 147. When this position is reached the valve stem 146 engages the trip bar 148, causing air to enter the suction cup 144, thus removing the suction which causes the container to adhere to the suction cup and permitting the container to fall into the discharge hopper 147 where the container is picked up for use.

After the completed container is removed from the machine, the turret 6 is again advanced one-sixth of a revolution to present the mandrel, from which a completed container was removed to position to receive another paper sleeve 1 to begin another cycle of operations to produce another container.

Having now described my invention, I claim:

1. In a machine for making cylindrical, paper containers of the character described, comprising means for positioning a paper sleeve on the end of a mandrel mounted on a horizontally rotatable turret, apparatus for cutting, forming and inserting a bottom disc into the end of the sleeve, a crimping tool for turning one end of the sleeve inward, means for positioning a second paper sleeve over the first sleeve on the mandrel, a second crimping tool for crimping adjacent ends of the sleeves tightly against the bottom disc, and a device for drawing the container from the mandrel.

2. In a machine for making double walled, cylindrical, paper containers; a base frame having a horizontally rotatable turret mounted thereon; six horizontally extending mandrels secured to and spaced equidistant about the turret; a device for placing inner wall, paper sleeves singly and successively upon the mandrels, leaving the outwardly extending ends of the sleeves free of the mandrels; a die for cutting bottom discs from a web of paper; a former block and a former ring for forming a flange on each bottom disc; means for advancing each formed bottom disc from the former ring and inserting it within the end of the corresponding paper sleeve; a crimping tool for turning the free end of each sleeve slightly inward; a device for sliding an outer wall paper sleeve over each inner wall paper sleeve; a crimping tool for crimping the free ends of the inner and outer wall sleeves tightly over the flange on the bottom disc; and a device for drawing the completed containers singly and successively from the mandrels.

3. In a machine for making double walled, cylindrical, paper containers; a base frame having a horizontally rotatable turret mounted thereon; six horizontally extending mandrels secured to and spaced equidistant about the turret; a device for placing inner wall, paper sleeves singly and successively upon the mandrels, leaving the outwardly extending ends of the sleeves

free of the mandrels; means for cutting, forming and inserting a bottom into the free end of each paper sleeve; a crimping tool for turning the free end of each sleeve slightly inward; a device for sliding an outer wall paper sleeve over each inner wall paper sleeve; a crimping tool for crimping the free ends of the inner and outer wall sleeves tightly over the bottom disc; and a device for drawing the completed containers from the mandrels.

4. In a machine for making double walled, cylindrical, paper containers; a base frame having a horizontally rotatable turret mounted thereon; a plurality of horizontally extending mandrels secured to and spaced equidistant about the turret; a device for placing inner wall paper sleeves singly and successively upon the mandrels, leaving the outwardly extending ends of the sleeves free of the mandrels; means for cutting, forming and inserting a bottom into the free end of each paper sleeve; a crimping tool for turning the free end of each sleeve slightly inward; a device for sliding an outer wall paper sleeve over each inner wall paper sleeve; a crimping tool for crimping the combined free ends of the inner and outer wall sleeves against the bottom disc; and mechanism for drawing the completed containers from the mandrels.

5. In a machine for making double walled cylindrical paper containers, a base frame having a rotatable turret mounted thereon; a plurality of outwardly extending mandrels secured to and spaced about the turret; a device for placing inner wall paper sleeves singly and successively upon the mandrels, leaving the outwardly extending ends of the sleeves free of the mandrels; means for cutting, forming and inserting a bottom into the free end of each paper sleeve; a crimping tool for turning the free end of each sleeve inwardly; a device for sliding an outer wall paper sleeve over each inner wall paper sleeve; and a crimping tool for crimping the combined free ends of the inner and outer wall sleeves against the bottom disc.

6. In a machine for making double walled, cylindrical paper containers; a base frame having a rotatable turret mounted thereon; a plurality of outwardly extending mandrels secured to and spaced about the turret; a device for placing inner wall paper sleeves singly and successively upon the mandrels, leaving the outwardly extending ends of the sleeves free from the mandrels; means for cutting, forming and inserting a bottom into the free end of each paper sleeve; a device for sliding an outer wall paper sleeve over each inner wall paper sleeve; and a crimping tool for crimping the combined free ends of the inner and outer wall sleeves against the bottom disc.

7. In a machine for making double walled, cylindrical paper containers; a base frame having a rotatable turret mounted thereon; a mandrel secured to the turret; means for positioning an inner wall paper sleeve upon the mandrel, leaving one end of the sleeve free of the mandrel; a die for cutting bottom discs from a web of paper; a former block and a former ring for making a flange on each bottom disc; means for advancing each formed bottom disc from the former ring and inserting it within the free end of the paper sleeve; a crimping device for turning the free end of the sleeve slightly inward; a device for sliding an outer wall paper sleeve over the inner wall paper sleeve; a crimping tool for

crimping the free ends of the inner and outer wall sleeves tightly over the flange on the bottom disc; and a device for drawing the completed container from the mandrel.

5. 8. In a machine for making double walled, cylindrical, paper containers; a base frame having a rotatable turret mounted thereon; a mandrel secured to the turret; means for positioning an inner wall paper sleeve upon the mandrel; 10 leaving one end of the sleeve free from the mandrel; apparatus for cutting, forming and inserting, a bottom disc within the free end of the sleeve; a crimping device for turning the free end of the sleeve slightly inward; a device for sliding an outer wall paper sleeve over the inner wall paper sleeve; and a crimping tool for crimping the free ends of the inner and outer sleeves tightly 15 against the bottom disc.

9. In a machine for making double walled, cylindrical, paper containers; a base frame having a rotatable turret mounted thereon; a mandrel secured to the turret; means for positioning an inner wall paper sleeve upon the mandrel, leaving one end of the sleeve free from the mandrel; means for inserting a bottom disc within the free end of the sleeve; a crimping device for turning the free end of the sleeve slightly inward; a device for placing an outer wall paper sleeve over the inner wall paper sleeve; and a crimping tool for crimping the free ends of the combined inner and outer sleeves tightly against the bottom disc.

35 10. In a machine for making double walled, cylindrical, paper containers; a base frame having a rotatable turret mounted thereon; a mandrel secured to the turret; means for positioning an inner wall paper sleeve upon the mandrel leaving one end of the sleeve free from the mandrel; means for inserting a bottom disc within the free end of the sleeve; a device for positioning an outer wall paper sleeve over the inner wall paper sleeve; and a crimping tool for crimping the free ends of the combined inner and outer sleeves tightly against the bottom disc.

40

45 11. In a machine for making double walled, cylindrical, paper containers; a mandrel for holding the container elements in position while the container fabricating operations are being performed; a device for positioning an inner wall paper sleeve upon the mandrel, leaving one end of the sleeve free from the mandrel, means for inserting a bottom element within the free end of the sleeve; a crimping tool for turning the free end of the sleeve slightly inward; a device for positioning an outer wall paper sleeve over the inner wall paper sleeve; and a crimping tool for crimping the free ends of the combined inner and outer sleeves tightly against the bottom element.

50

55

60 12. In a machine for making double walled cylindrical paper containers; a mandrel for holding the container elements in position while the container fabricating operations are being performed; a device for positioning an inner wall paper sleeve upon the mandrel, leaving one end of the sleeve projecting from the end of the mandrel; means for inserting a bottom element within the projecting end of the sleeve; a sleeve assembling device for pressing an outer wall paper sleeve over the inner wall paper sleeve; and a crimping tool for crimping the projecting ends of the combined inner and outer sleeves tightly against the bottom element.

13. In a machine for making double walled paper containers; a mandrel for holding the con-

13

tainer elements in position while the container fabricating operations are being performed; means for pressing an inner wall paper sleeve over the end of a mandrel; means for inserting a bottom element within the paper sleeve; a sleeve assembling device for pressing an outer wall paper sleeve over the inner wall paper sleeve; and a crimping tool for crimping one end of the combined inner and outer sleeves tightly against the bottom element.

14. In a machine for making double walled containers; a mandrel for holding the container elements in position while the container fabricating operations are being performed; means for pressing a sleeve, comprising the inner wall of the container, over the end of the mandrel; a former block for inserting a bottom element within the sleeve; a tool for turning one end of the sleeve slightly inward over the bottom element; a sleeve assembling device for pressing an outer wall sleeve over the inner wall sleeve; and a tool for curling one end of the combined inner and outer sleeves tightly against the bottom element.

15. In a machine for making double walled containers; a base frame for supporting the several elements of the machine; a turret rotatably mounted on the base frame; a mandrel secured to the turret for holding the container elements

14

in position while the container fabricating operations are being performed; means for positioning a sleeve which comprises the inner wall of the container over the end of the mandrel; a former block for inserting a bottom element within the sleeve; a tool for turning one end of the sleeve slightly inward over the bottom element; a sleeve assembling device for pressing an outer wall sleeve over the inner wall sleeve; a tool for curling one end of the combined inner and outer sleeves tightly against the bottom element; and a suction cup operating device for drawing the container assembly off the end of the mandrel.

MELVIN H. SIDEBOOTHAM.
